No. 828,893.

PATENTED AUG. 21, 1906.

W. G. MARR.
SECTIONAL RIM.
APPLICATION FILED OCT. 9, 1905.

UNITED STATES PATENT OFFICE.

WILLIAM G. MARR, OF SPRINGFIELD, MASSACHUSETTS.

SECTIONAL RIM.

No. 828,893.

Specification of Letters Patent.

Patented Aug. 21, 1906.

Application filed October 9, 1905. Serial No. 281,887.

To all whom it may concern:

Be it known that I, WILLIAM G. MARR, a citizen of the United States of America, residing at Springfield, in the county of Hampden and Commonwealth of Massachusetts, have invented certain new and useful Improvements in Sectional Rims, of which the following is a specification.

My invention relates to improvements in rims for wheels for automobiles, cars, motorcycles, and vehicles, and comprises a sectional rim made in a suitable number of sections each attached in the center to the felly by certain resilient means and braced at the ends by adequate supports, all as hereinafter set forth; and the objects of my invention are, first, to provide a sectional and detachable rim; second, to provide suitable means for connecting each rim section and the felly and for holding them in place; third, to increase the resiliency of said rim. I attain these objects by the means illustrated in the accompanying drawings, in which—

Figure 1 shows said device in position on a section of the rim of a wheel, and Fig. 2 a cross-section of the rim at line x x.

Similar letters refer to similar parts throughout the views.

As before intimated, my rim is made up of a considerable number of sections. These sections are detachably held in place and to the felly upon which said rim is mounted by means of a plurality of pistons, cylinders, springs, nuts, or heads and supports or their equivalents. A detailed description of these parts will be found below.

My rim is divided into sections a a, each having at the center of its concave side a pin, piston, or rod a', said pin, piston, or rod a' being adapted to fit into and extend through a cylinder or tube b and the felly c, the cylinder b being attached to the felly c.

s represents a cover or cylinder, made of rubber or other suitable material, between the springs e e, designed to protect the rod a' and the cylinder or socket b from dust and mud.

The end of the piston a' which extends through the felly c is provided with a nut or head d, which holds the rim-section a from being forced outwardly beyond the normal position by the springs e e. The springs e e are placed between the periphery of the felly c and the adjacent part of the rim-section a and in such a manner as to force the piston-head or nut d against the felly c and the rim-

section a into its normal position. The sides of the rim-section a a are constructed flange-shaped, thereby forming a groove in which the tire-sections g are fastened. The 60 said flanges are supported in the center by a brace h, which runs laterally across the outer surface of the rim-section a and not only acts as a brace to the flanges, but also helps to hold the tire-sections g g in place. 65

f represents a support constructed at either end with a lip or projection i and being provided at the center of its concave side with a lug or projection j. The sides of the supports f are constructed flange-shaped similar to those of the rim-sections a a and engage the tire-sections g g in a similar manner. The support f is placed between the rim-sections a a, the lips i sliding on and supporting the adjacent surface of the rim-sections a a, and is held in place by means of a spring k or its equivalent. The spring k is placed between the support f and the felly c and is held in place by the lugs j and l. 70 75

A space is left between the ends of the supports and the adjacent ends of the rim-sections in order to allow one or more rim-sections and supports to give when exposed to a great amount of weight or pressure without affecting or injuring the others. 80

What I claim as my invention, and desire to secure by Letters Patent, is—

1. The combination with a wheel of a rim of sections, each section having a piston or rod the head or outer surface of which supports a part of the tire, the rim-sections being arranged alternately with supports, each support having a spiral spring and means for bearing against the adjoining rim-sections. 90

2. The combination with rim-sections each having a piston and a felly provided with cylinders or tubes and spiral springs interposed between the felly and inner surface of the rim-sections, of a series of supports arranged alternately with the rim-sections and having each a spiral spring and means for bearing against the rim-sections. 95 100

3. The combination with a sectional rim comprising a series of rim-sections having each a piston or rod, of a series of supports placed alternately with the rim-sections, each support having projections upon its surface toward the rim-sections which bear against the corresponding surfaces of the rim-sections and being provided with lugs 110 to hold springs in place and means to hold the tire upon the sections and supports, of a

felly provided with cylinders suitable to receive said pistons and having lugs or projections corresponding to the projections on the supports, of springs keeping the rim sections away from the felly, of springs keeping the supports in contact with the rim-sections, of nuts, heads or stops suitably attached to the

ends of said pistons so arranged as to prevent the sections and supports from being forced out of position.
